F. F. BADEN

ENDGATE

Filed March 17, 1927

UNITED STATES PATENT OFFICE.

FRED F. BADEN, OF PEORIA, ILLINOIS.

END GATE.

Application filed March 17, 1927. Serial No. 176,185.

This invention relates to end gates for wagons and trucks, having particular reference to an end gate made up of hingedly connected sections.

5 An object of the invention is to provide an end gate of sections hinged together, which while adapted to serve in the usual capacity of retaining materials carried by a vehicle, may be adjusted to positions whereby it may 10 act as a chute for dumping a flowable material at either side of such vehicle.

Another object is to provide an end gate of hinged sections which may be adjusted to positions for shoveling materials therefrom 15 either to the right or left of the vehicle and yet be employed in the same manner as is the ordinary form of rigid endgate.

To the end that my invention may be fully understood I have provided the accompanying drawing wherein

Figure 1 is a plan of a part of a vehicle body and my endgate in its closed position thereon.

Figure 2 is a rear elevation of the endgate when used as a closure for the vehicle body.

Figure 3 is a plan on a smaller scale of a portion of the vehicle body and my end gate when used as a chute or for shoveling materials from the vehicle at one side.

Figure 4 is a detail in section of a hinge connection taken on lines 4—4, Figure 2.

Figure 5 is a side elevation of part of the vehicle body, and the end gate as positioned in Figure 3, and

Figure 6 is a rear elevation of said body and end gate showing the latter again as positioned in said Figure 3.

Quite often it is desired that materials such as sand, gravel, earth and the like be delivered toward one side of the vehicle rather than directly in the rear thereof. I have therefore devised an end gate of hinged sections that can be adjusted for use as a chute for the above purpose but which can be used as a flat shoveling board when desired.

The characters 1 and 2 designate the sides and bed, respectively, of a vehicle whether a truck or wagon, while 3 may be any suitable upright stay from which to suspend the end gate to be described, as will appear later.

The end gate as I construct it consists of sections hingedly connected, there being 55 shown in the present instance four of such

sections denoted by 4, 5, 6 and 7 all hinged together as shown in Figure 2, the whole forming a rectangular member of the size required for any given size of vehicle body. The section 4 at its top edge constitutes the 60 upper edge of the end gate while its opposite edge is cut at an angle in opposite directions coming together at the middle of its width in a point in the form of an inverted A. The section 5 is similarly formed the points of 65 both sections lying adjacent one another, the straight edge of said section 5 being hinged to the bed 2 of the vehicle. The sections 6 and 7 are identical in form, triangular, and lie in the angular spaces between the said 70 sections 4 and 5, the adjacent edges of the several sections being substantially parallel and hinged to one another.

The type of hinge for connecting the several sections to one another and for connecting the section 5 to the vehicle bed 2 may be as shown in Figure 4 wherein 8 and 9 indicate a plurality of closely placed U-shaped straps connected to the parts as by rivets 10 and preferably let into the parts so as to present a flush surface for the endgate throughout, while a hinge pin 11 extends through all of the straps from end to end.

As an aid in the understanding of the adjustments to be described the hinge connecting the section 5 to the bed 2 is denoted in general by the character 12, the hinge connecting the sections 4 and 6 by the character 13, the hinge between the sections 4 and 7 by 14, and that connecting 6 and 5 by 15, while 90 the hinge between sections 7 and 5 is denoted by 16.

It will be readily seen that the sections 4 and 7 as a unit may hinge upon and with respect to the sections 6 and 5 through the 95 hinges 13 and 16 as shown in Figures 3, 5 and 6. That is to say, the sections 5 and 6 may be lowered so as to lie in the same plane as the bed 2, Figure 5; and the sections 4 and 7 may take a substantially vertical position. In this position of the sections the end gate answers as a chute for discharging a load toward the left side of the vehicle as viewed in the drawing, that position being maintained through the use of a chain 105 17, for example, attached to an eye 18 on the section 4 and a hook 19 on the upright stay 3 as shown at the right of Figure 3. The gate is thus held so that the sections 5 and 6 form the floor of the chute while the sec- 110

tions 4 and 7 form a rear stop for preventing the material discharged from leaving the vehicle body rearwardly.

The position of the parts may be reversed so that the delivery of the load may be toward the right in which event the sections 5 and 7 will constitute the floor portion of the constituted chute while sections 4 and 6 form the stop portion at the rear. This alternative position is indicated in broken lines in Figures 3 and 6, it being required that the hinges 15 and 14 be used in lieu of hinges 13 and 16 as before. In this event, also, the chain 17 at the opposite side is used as the supporting means as will be well understood.

If it is desired that an end gate be constructed for permanent delivery at one side only the said gate may be constructed of but two sections using but one continuous hinge as 13-16 or 15-14 depending upon the desire. In other words the end gate may include but one of the diagonally arranged hinged joints.

25 When the end gate is used to close the end of a vehicle body a rod 20 is employed which is inserted through keepers 21 and 22 on the sections 4 and 5 respectively, maintaining all of the sections in a single plane and relatively rigid.

Likewise the rod 20 may be used at such times as it is desired to suspend the entirely flat end gate horizontally from the vehicle for use as a shoveling board, longer chains, 35 not shown, being employed for such suspension.

I claim:

1. An end gate for vehicles severed diagonally in two opposite directions, the lines 40 of separation crossing one another, and hinging members connecting the resultant sections.

2. An end gate for vehicles severed diagonally from a position at one edge near its base line to an opposite edge, and hinging members connecting the separate sections.

3. An end gate for vehicles substantially rectangular in form consisting of two parts each having an edge inclined at an angle 50 to its base line, the inclined edge of one being hingedly connected to the inclined edge of the other, the said edges thus connected extending diagonally of the structure.

4. An end gate for vehicles having a substantially rectangular form comprising two parts each having an edge inclined at an angle to its base line, the inclined edges of both paralleling one another, and hinge members connecting the parts at said edges, 60 said edges extending substantially diagonally from one edge to the other of said gate.

5. An end gate of substantially rectangular form consisting of hingedly connected sections, the hinged edges of the sections extending diagonally of, across and through

the gate from one of its side edges to the other.

6. An end gate of substantially rectangular form for vehicles consisting of hingedly connected independent sections, one of them 70 adapted to be hinged to the vehicle, the joined hinged edges of the sections extending diagonally across the gate at an angle to the edge having attachment to said vehicle. 75

7. An end gate for a wagon body consisting of four hingedly connected sections, the connected edges of such sections extending diagonally of the end gate in opposite directions, all of the sections adapted to lie 80 in a single plane when the end gate is closed upon the end of said body.

8. An end gate of substantially rectangular form consisting of four hingedly connected sections, the connected hinged edges 85 of such sections extending diagonally across the end gate at opposite angles, the line of separation of the edges crossing one another.

9. An end gate of substantially rectangular form for vehicles consisting of hingedly connected independent sections, one of them 90 adapted to be hinged to a vehicle, the joined hinged edges of the sections extending diagonally across the gate at an angle to the edge having attachment to said vehicle, and means to secure the sections relatively rigid.

10. An end gate of substantially rectangular form for vehicles consisting of hingedly connected independent sections, one of them 100 adapted to be hinged to the vehicle, the joined hinged edges of the sections extending diagonally across the gate at an angle to the edge having attachment to said vehicle, and means to secure the sections 105 relatively rigid in one plane.

11. An end gate of substantially rectangular form consisting of four hingedly connected sections, the connected hinged edges 110 of such sections extending diagonally across the end gate at opposite angles, the line of separation of the edges crossing one another, and means to secure the sections relatively rigid when all are lying in the same plane.

12. An end gate for a vehicle body 115 consisting of four sections hinged to one another, the lines of the hinged edges extending diagonally in opposite directions from opposite side edges of said gate and crossing one another, one of the said sections being hinged to the vehicle body, means to suspend the end gate from the said body with the last named section substantially parallel to the floor of the same, certain of the sections in such suspended position adapted to 120 have a position perpendicular to said last named section and lying at an angle to the side members of said body.

In testimony whereof I affix my signature.
FRED F. BADEN.
